UNITED STATES PATENT OFFICE.

EUCLID JEROME LOWE, OF BALBOA, CANAL ZONE.

PROPELLER.

1,217,790.

Specification of Letters Patent. Patented Feb. 27, 1917.

Application filed November 10, 1915. Serial No. 60,708.

To all whom it may concern:

Be it known that I, EUCLID J. LOWE, a citizen of the United States, and a resident of Balboa, Panama, Canal Zone, have invented a new and Improved Propeller, of which the following is a full, clear and exact description.

My invention has for its object to provide a propeller especially adapted for use on aeroplanes, which has a flange extending forwardly of the forward edge of the propeller blade, the propeller blade being concave longitudinally and transversely, and ribs being provided at the convex face of the 15 blade to stiffen the latter.

Another object of the invention is to provide the hub with flattened surfaces at each side to obtain shoulders for the base ends of the ribs.

Still other objects of the invention will appear in the following specification, in which the preferred form of my invention is described.

In the drawings similar reference characters refer to similar parts in all the views, in which—

Figure 1 is a plan view of my propeller; Fig. 2 is a front view of the propeller; and Fig. 3 is a sectional view on the line 3—3 30 of Fig. 1.

By referring to the drawings, it will be seen that my propeller is provided with a hub 5 and a blade or blades 6, the number of the blades with which the propeller is provided being immaterial, and the propeller blades are provided without pitch. At the front edge of each of the propeller blades, there is a flange 7 which extends forwardly of the concave face of the blade, from the hub 35 to the outer end 8 of the propeller blade and then along the outer edge of the blade to the rear edge 9 of the blade. This flange extends forwardly of the blade, as has been stated, and cuts directly into the medium in which 40 the propeller is rotated, the air or other medium in which the propeller is rotated being compressed within the concave face of the blade, the compressed air or other medium being prevented from escaping at the outer 45 end of the blade by the flange 7, which extends from the front edge 8 to the rear edge 9 at the blade's outer edge. As there is no obstruction at the concave face of the blade in the rear of the forward flange 7, the air 50 which has been compressed along this concave face of the blade is forced rearwardly,

which causes the propeller to travel in a forward direction in a manner well understood. The propeller blade, therefore, compresses the atmosphere and drives this compressed atmosphere rearwardly without reference to pitch or skin friction. While the blades are concaved only slightly parallel with the axis of the propeller, the blades are concaved considerably at right angles to the axis of 65 the propeller.

I prefer to construct my propeller of metal and in order to make the propeller blades rigid, I provide the convex face of each of the blades with stiffening ribs 10, which extend from the hub 5 in the direction of the outer end of the blade. I also prefer to flatten the sides of the hub 5 at 11 to receive the face ends of the ribs 10.

The propeller has continuous motion. The 75 blades proper have no pitch. The flange or shoulder on each blade is subject to pitch. The faces of the blades against the atmosphere are concave both laterally and longitudinally. The blades have a shoulder or 80 flange on their forward edges and in revolving go square against the atmosphere, which causes pressure in the crown and also the same pressure against the shoulder or flange. There is no obstruction behind this shoulder, 85 consequently the air escapes behind as compression takes place, said action causing the propeller to move forward. The propeller compresses the atmosphere as it revolves and 90 discharges it behind.

It should be understood that the concave surfaces of the blades strike against the air, and that the ribs are on the rear or convex surfaces of the blades.

Having thus described my invention, what 95 I claim as new and desire to secure by Letters Patent, is:

1. A propeller having a blade without pitch, and flanges extending in the general direction of rotation from the front and the 100 outer edges of the blade.

2. A propeller having a concave blade without pitch, and flanges extending in the general direction of rotation from the front and the outer edges of the blade. 105

3. In a propeller, a hub having a flattened side, a blade extending from the hub at the said side, a flange extending forwardly of the forward edge of the blade, and a rib on the blade abutting against the said side of 110 the hub.

4. A propeller having a blade without

pitch and a flange extending in the general direction of rotation from the front of the blade.

5. A propeller having a concave blade without pitch and a flange extending in the general direction of rotation from the front edge of the blade.

6. A propeller having a blade concave longitudinally and transversely, and a flange extending forwardly from the front edge of the concave face of the blade.

7. A propeller having a blade concave longitudinally and transversely, and a flange extending forwardly from the front edge to 15 the outer end of the concave face of the blade.

8. A propeller having a blade concave transversely of the axis of the propeller, and a flange extending forwardly from the front edge of the concave face of the blade.

9. A propeller having a blade concave transversely of the axis of the propeller, and a flange extending from the front edge to the outer end of the concave face of the blade.

In testimony whereof I have signed my 25 name to this specification in the presence of two subscribing witnesses.

EUCLID JEROME LOWE.
